Batholoma Scembert of New York, N.Y.
Letters Patent No. 2478. Dated Oct. 2, 1866.
Design for a reel.

The schedule refers to in the above Letters Patent and, making part of the same.

To all whom it may concern:

Be it known that S. Batholoma Scembert of the City of New York, in the County and State of New York have originated and designed for a Trade Mark a new Reel for ribbons, trimmings and similar articles of which the following is a full, clear and exact description reference being had to the

accompanying drawings making part of this Specification.

This new Reel is made of sheet iron or base metal, straight, whether sides and top part B, form a segment of a circle, the corners a, a, where the arc joins the bottom on base A, are made slightly rounded as represented.

This Reel is used for cords, tape, ribbons, trimmings and similar articles.

What I claim as my invention and desire to secure by Letters Patent, is
The Design for a reel for tape, ribbons, trimmings &c, as a Trade mark as herein set forth and shown.
